UNITED STATES PATENT OFFICE

170,360

LAMP PENDANT

Irving Levin, New York, N. Y.

Application January 31, 1952, Serial No. 18,316

Term of patent 14 years

(Cl. D48—3)

To all whom it may concern:

Be it known that I, Irving Levin, a citizen of the United States of America, residing in the Borough of Manhattan, city of New York, county of New York, and State of New York, have invented a new, original, and ornamental Design for a Lamp Pendant, of which the following is a specification, reference being had to the accompanying drawing, forming part thereof.

Figure 1 is a front elevational view of a lamp pendant showing my new design; Figure 2 is a side elevational view thereof; Figure 3 is a rear elevational view thereof; Figure 4 is a plan view thereof; Figure 5 is a sectional view thereof as seen from the plane 5—5 on Figure 2; and Figure 6 is a sectional view thereof as seen from the plane 6—6 on Figure 3.

I claim:

The ornamental design for a lamp pendant, as shown.

IRVING LEVIN.
